TRAY OR SIMILAR ARTICLE

Robert L. Gruen, New York, N. Y., assignor to Continental Silver Co. Inc., a corporation of
New York

Original No. 167,206, dated July 8, 1952, Serial No.
17,424, November 15, 1951. Application for reissue August 8, 1952, Serial No. 20,959

1 Claim. (Cl. D44—10)

To all whom it may concern:

Be it known that I, Robert L. Gruen, a citizen of the United States and residing at New York, in the county of New York and State of New York,
have invented a new, original, and ornamental Design for Tray or Similar Article, of which the following is a specification, reference being had to the accompanying drawings, forming part thereof, and in which

Fig. 1 is a perspective view of a tray or similar 10 article, showing my new design,

Fig. 2 is a top plan view,

Fig. 3 is a side elevational view, and

Fig. 4 is a transverse vertical sectional view thereof, taken along line 4—4 of Fig. 1.

The dominant feature of my design resides in the grooved inlay ornamentation placed along the longitudinal axis of the tray, as shown.

I claim:

The ornamental design for a tray or similar 20
article, substantially as shown and described.

ROBERT L. GRUEN.
